UNITED STATES PATENT OFFICE

EDWARD K. ABEL, OF JACKSONVILLE, FLORIDA

STENCIL-CUTTING DEVICE

Application filed January 27, 1928. Serial No. 249,995.

The present invention relates to improvements in stencil cutting devices, and has for an object to provide an illuminated board or support for holding the pattern and stencil whereby the stencil may be prepared for the mimeograph machine. The invention is also applicable to drafting boards and the like.

The chief purpose of the invention is to provide a device of this kind which will be readily portable, compact in size and construction, simple and light in form, yet possessing substantial strength.

Other objects of the invention are to produce an improved light yet strong illuminating casing, to provide an improved board construction on such casing and to improve the clamp construction for the glass base or board.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of an improved device constructed according to the present invention.

Figure 2 is a side elevation of the same.

Figure 3 is a bottom plan view.

Figure 4 is a longitudinal central section taken through the device.

Figure 5 is a top plan view of the illuminating casing with the top board removed.

Figure 6 is an enlarged fragmentary cross section taken on the line 6-6 in Figure 1, and

Figure 7 is an enlarged longitudinal fragmentary section taken of the left upper corner of Figure 4.

Referring more particularly to the drawings the device is composed generally of a casing and a board supported thereon.

The casing is shown to have a bottom 8, end walls 9 and 10 and side walls 11 and 12. The casing is preferably made from thin sheet metal which is recommended for its lightness and portability.

The walls of the casing are shallow so as to adapt the device to be placed upon a desk,

table or other convenient support without raising the board on which the work is done to too great an elevation. Feet 13 of rubber or other material and rounded or of other form are provided at the four corner portions 55 of the casing bottom to not only avoid marring the support upon which the device is placed but also to afford a cushioned and yielding effect to the entire device.

It will be noted, from examination of Figures 2 and 4 that the upper edge of the casing is disposed on an inclination, the end wall 9 being lower as to height than the opposite end wall 10, and the upper edges of the side walls 11 and 12 inclining accordingly from one 65 end wall to the other. The board is thus supported on an inclination, as shown.

Now the thin walls of the portable table are required to support the rather heavy board, the same being also called upon to provide attachment to the board. The upper edges of the walls are, with these ends in view, constructed to reinforce the casing, as shown in Figure 5, in which the flanges 14, 15 and 16 extend at right angles to the respective 70 planes of the side walls 11, 12 and the end wall 9. The flanges referred to are bent outwardly from the several walls and perforated as indicated at 17 to receive screws, or other fastenings, by which the flanges and the casing as a whole are secured to the lower surface 75 of the board.

Now it will be noted that the flanges 14 and 15 do not extend the entire length of the side walls 11 and 12, but they terminate short of 85 the lower end wall 9. In initially stamping the casing from the blank of sheet metal material of which it is made, the upper edges of the side walls throughout are formed with the flanges, but after the stamping operation, 90 such flanges are cut through along transverse lines indicated at 18 and 19 and the portions of the flanges between the points 18 and 19 and the end wall 9 are folded or bent down outwardly upon the exterior surfaces of the 95 respective end walls 11 and 12. This construction is clearly shown in Figure 2. This doubled construction stiffens and reinforces the upper edges of the side walls 11 and 12 and stiffens the casing as a whole in a longi- 100

tudinal direction. Preferably the lower end wall 9 is not provided with any stiffening members as owing to the proximity of the stiffening flange portions 20 and 21 of the side walls, no particular strength is needed in the shorter end wall 9.

However, the opposite or higher end wall 10 is provided with a flange 22 which is folded over outwardly and downwardly against the outer surface of the upper edge of the wall and is pressed tightly thereagainst to form a double ply upper reinforced edge. This flange 22 not only stiffens the wall 10, but also the entire casing in a transverse direction. The attaching flanges 14 and 15 of the side walls extend to the end wall 10, which is provided with a stiffening flange 22, but they do not extend to the opposite end wall 9 which is unprovided with any stiffening flange. The offsetting of the side stiffening flanges 20 and 21 from the end stiffening flange 22 enables the upper casing wall edges to provide a sufficient integral attaching surface to the board, while also affording ample strength in the light sheet metal casing.

The board is made in sections of which 23 and 24 are side styles and 25 and 26 head pieces. The ground glass or other transparent or translucent board proper is indicated 30 at 27. The side styles are provided with the reduced ends 27 and 28, mortises being made in the upper surfaces thereof to receive the tongues 29 and 30 of the head pieces 25 and 26.

As shown in Figure 3 screws or other fastenings 31 and 32 are provided to hold the overlapped parts together. As also shown in Figure 3 screws or other fastenings 33, 34 and 35 are employed to secure the attaching flanges of the casing to the side styles and head piece 26 of the board.

The head piece 25 is provided with the usual means for attaching the end of the stencil and tracing which are superposed upon the board 27 for the purpose of cutting and preparing the stencil for its use in the mimeograph machine.

The side styles 23 and 24 are provided with longitudinal similar slots 36 which extend into the head piece 26. These slots are formed 50 at one end with the enlarged rounded perforations 37.

Clamps 38 for the glass 27 are provided with shanks 39 fitting slidably in the slots 36. Washers 40 and 41 extend about each 55 shank 39 below the style bar; and between the washers 40 and 41 are wound coil springs 42. The ends of each shank 39 are split and over-turned in opposite directions, as indicated at 43 and 44, particularly in Figure 3.

An electric lamp 45 or other source of illumination is mounted in the casing, the interior of which is preferably tinned, mirrored or coated with some other bright substance to heighten the effect of the lamp and to brightly reflect the image on the glass.

A lamp socket is indicated at 46 being attached to the end wall 10. The wires or leads 47 enter through a plug 48 in the side wall 12. The cable may be coupled to any electric socket or outlet.

The ends 49 and 50 of the glass 27 are beveled as shown in Figure 4. The beveled end 49 fits against the beveled undercut lugs 51 and 52 upon the head piece 25. A separate metal or other clamp piece 53 is carried by the intermediate portion of the head piece 26 and provided with a downwardly bent overhanging end for engaging against the beveled end 50.

In the use of the device, a drawing, or other master sheet and stencil are placed upon the frosted glass 27, the lamp 45 being energized as by connecting it to the house light circuit. The stencil may then be cut. The inclination at which the board is supported, the use of the yieldable feet 13 and the elevation at which the device is supported upon an ordinary desk or table top will lend conjointly to the easy and quick cutting of the stencil.

When the need for transportation arises, the device will be found readily portable by reason of its light weight and small size; yet when the pressure of the hands and body are put upon the board, the stiffness and reinforcement in the casing will resist any tendency of the walls to buckle or crumple. The clamps 38 may be adjusted along the slots 36 and may be taken out through the openings 37 when required. The casing may be removed by unfastening the screws 33, 34 and 35 to give access to the interior of the casing for replacing bulbs, etc.

The ground glass 27 may also be removed by removing the clips 38 and the keeper piece 52 which is held to the head 26 by a screw or other fastening.

It is obvious that various changes and modifications may be made in the details of construction and design of the above specifically described embodiment of this invention without departing from the spirit thereof, such changes and modifications being restricted only by the scope of the following claims.

What is claimed is:—

1. A stencil cutting device comprising a shallow casing to rest upon a table or the like, said shallow casing constructed of light opaque material and provided with an outwardly projecting narrow flange along the upper edge of one end and the side walls, a source of illumination contained within said shallow casing, an open rectangular frame having elongated slots adjacent one end secured to said narrow flanges and projecting outwardly beyond same, a translucent supporting board carried by said frame, and spring pressed clips movable in said elongated slots to hold sheets of various lengths above said translucent supporting board.

2. A stencil cutting device comprising a

shallow casing having its bottom, ends and side walls of thin metal, one of said end walls being lower in height than the other, and provided along its upper edge with an outwardly projecting narrow flange, said side walls inclining from one end wall to the other and provided along its upper edge with an outwardly projecting narrow flange cut away adjacent said lower end wall, a source of illumination contained within said shallow casing, a frame comprising side styles and head pieces attached to said narrow flanges and extending outwardly beyond same, a translucent supporting board carried by said frame, said side styles and head piece adjacent the lower end of said frame provided with elongated slots, and spring pressed clips movable in said elongated slots to hold sheets of various lengths above said translucent supporting board.
